UNITED STATES PATENT OFFICE.

GEORGE F. CONNER, OF PORT HURON, MICHIGAN.

SPARK ARRESTER AND EXTINGUISHER.

SPECIFICATION forming part of Letters Patent No. 663,148, dated December 4, 1900.

Application filed March 1, 1900. Serial No. 6,971. (No model.)

To all whom it may concern:

Be it known that I, GEORGE F. CONNER, a citizen of the United States, residing at Port Huron, in the county of St. Clair and State of Michigan, have invented certain new and useful Improvements in Spark Arresters and Extinguishers, of which the following is a specification.

This invention relates to an improvement in spark arresters and extinguishers; and it consists in the peculiar construction and arrangement of parts hereinafter described, and definitely pointed out in the claim.

The invention relates particularly to that class of spark-arresters which have a conical sieve or reticulated depression at the center, with means for conducting the sparks back down to the stack; and the present invention is to provide a very simple, efficient, and durable construction of the type above described which will contain a relatively few number of different parts.

In the drawing I have shown the construction in longitudinal vertical section, parts being shown in elevation.

In the drawing, A represents a smoke-stack having securely riveted to its upper edge an outwardly-flaring casting a , the same being inclined upwardly and formed at its upper edge with a circumferential angular seat a' , while the lower portion directly above the connection with the pipe A is formed with the horizontal seat a^2 , having a substantially vertical side wall a^3 . On the seat a' is secured a tapering cylinder or casing B, the same being riveted to the edge of the casting a and extending upwardly to the top of the stack. On the upper end of this cylinder B is secured a circular cap or ring C of conical formation in cross-section, the outer edges being flared outwardly horizontally and resting on the corresponding edges on the top of the cylinder B. To secure the cap in place, pivoted clips or hooks C' are secured to the cylinder, having their upper ends sprung over and engaging the upper surfaces of the flanges of the ring. At this point suitable raised projections c are formed on the flange, over which the ends of the clips engage, so as to form secure connections.

Rising from the joint between the pipe A and casting a and having its lower edge se-

cured in the seat a^2 is a vertical partition E, slightly inclined outwardly and of circular formation. This partition extends upwardly 55 to a point adjacent to the ring C, but slightly below the same, leaving a passage-way between. In the lower portion of the partition are formed a series of openings D'. The partition is securely fastened in place by rivets 60 passing through the vertical walls a^3 of the casting in the lower edge of the partition.

Secured to the inner periphery of the ring C is a depending conical-shaped deflector F, made of wire conveniently and strengthened 65 by vertical metallic stays f, to which it is secured, which latter are secured by suitable rivets to the ring. This deflector has on its lower end an imperforate pointed extension F', constituting the apex of the cone and to 70 which the lower ends of the stays are fixedly secured.

In operation the imperforate point of the deflector is in line with the axis of the pipe A, and as the sparks are forced upward by 75 the draft the same engage or strike against the inclined walls of the deflector and are carried upward onto the inclined faces of the ring C outward and fall down in the space between the partition and cylinder B. They 80 are then projected through openings at the base of the partition and fall downward through the pipe a at the sides. They are finally broken by repeated circulation or by impingement against the inclined surfaces of 85 the arrester or dropped down to the bottom of the stack, where they are collected in any suitable receptacle.

Having thus described my invention, what I claim as new, and desire to secure by Letters 90 Patent, is—

In a spark-arrester, the combination with a stack, of a casting secured to the upper edge thereof, a tapered cylindrical casing supported from the upper edge of the casting, an 95 outwardly-extending flange on the upper edge of the casing, an inverted-V-shaped annular ring, a flange on one edge of the V adapted to rest on the corresponding flange of the casing, a deflector secured to the opposite edge 100 of the V so as to be detachable therewith, means for temporarily retaining the ring on the casing comprising clips exterior of the casing arranged to overlie the flange of the

ring, and a partition provided with openings at its lower end secured to the casting and extending upwardly between and unattached to the deflector and casing to a point directly beneath and in the hollow of the annular ring, substantially as and for the purpose described.

In testimony whereof I affix my signature in presence of two witnesses.

GEORGE F. CONNER.
